UNITED STATES PATENT OFFICE.

THOMAS H. KINGSTON, OF WEST SOMERVILLE, MASSACHUSETTS.

PUTLOG.

1,077,839.

Specification of Letters Patent.

Patented Nov. 4, 1913.

Application filed April 4, 1913. Serial No. 758,836.

To all whom it may concern:

Be it known that I, THOMAS H. KINGSTON, a citizen of the United States, and a resident of West Somerville, in the county of Middlesex and State of Massachusetts, have invented certain new and useful Improvements in Putlogs, of which the following is a specification.

My present invention has reference to improvements in putlogs and particularly to putlogs employed in the erection of brick or masonry walls.

The objects of the invention are to provide a putlog having one end adapted to be inserted and firmly anchored in a wall and a plank or floor supporting portion adapted to be swung independently of said end and at any desired horizontal angle to the wall; which may be readily attached to or removed from a brick wall without injury thereto and which is simple, durable and strong.

Other objects of the invention will appear from the following description.

The invention consists in a plank or floor supporting bar provided with a hinged anchor plate and in such other novel features of construction and combination of parts as shall be hereinafter more fully described and pointed out in the claims.

Referring to the drawings in which like numbers of reference designate corresponding parts throughout, Figure 1 is a plan view illustrating a customary form of scaffolding erected about a brick wall in course of construction and the application of several putlogs thereto. Fig. 2 is a perspective view further illustrating the application of my invention. Fig. 3 is a perspective view of the end of the putlog which is applied to the wall. Fig. 4 is a side elevation of the same. Fig. 5 is a top plan view of the same. Fig. 6 is a section on the line 6—6 of Fig. 5. Fig. 7 is a section on the line 7—7 of Fig. 4 and Fig. 8 is a view similar to Fig. 7 of the inner end of a wider putlog.

In a preferred form of the invention, 10 designates the floor supporting bar. At one end of said bar a rectangular portion is cut away from the under side thereof thus forming the projection 11.

The U-shaped metallic reinforcing stirrup 14 is secured to the latter by the rivet 12 and by the vertical rivet 13 in such a manner as to leave a space 15 between the under side of said projection and the horizontal side of said stirrup. Said vertical rivet extends

through said projection, through the aperture in one end of the anchor plate 16 which extends into said recess 15 and through the horizontal side of the stirrup 14. The portion of said vertical rivet which passes through said aperture in the anchor plate serves as a pivot therefor, and the portion of said anchor plate which is within said recess is substantially of the same height as said recess so that said anchor plate may be swung horizontally, but is prevented from moving vertically or having any play on said pivot by the under side of the projection 11 and by the horizontal side of the stirrup 14. Said anchor plate is further prevented from moving vertically by the transverse reinforcing rivet 17 which extends through the horizontal slot 18 in said anchor plate and through the vertical sides of said stirrup, the width of said slot being substantially the same as the diameter of said reinforcing rivet so as to prevent any vertical play between said slot and said rivet and the length of said slot being enough to allow sufficient lateral angular movement of said anchor plate. Said anchor plate is cut away to form the bearing edge 19; the recess 20 adjacent the inner end of said bearing edge and the downwardly projecting lug 21 on the free end of said anchor plate. The upper edge of the free end of the latter is beveled at 22.

In the use of the putlogs the customary uprights 23 and ledgerboards 24 of the scaffold are erected beside the partially constructed wall 26 and then the anchor plate 16, if the wall be of brick, is inserted between two bricks 27, of the outer vertical layer until it butts against the second vertical layer when it is moved downwardly until the bearing edge 19 rests upon the top of the brick 28. The latter movement brings the lug 21 down between said two vertical layers of bricks. The thickness of said anchor plate is substantially the same as the width of the interstices between the bricks and the beveled edge 22 allows said anchor plate to be readily inserted.

It is to be understood that it is not necessary to leave out, to displace or in any way injure a brick in order to insert the anchor plate and that said plate is prevented from moving laterally, downwardly or outwardly after being inserted, and that, although said plate is held firmly, the floor supporting bar 10 may be swung laterally as desired. The

latter movement is one of the main features of the invention as it is often desirable to secure the outer end of the putlog to an upright by a spike or other suitable means, 5 and this would be impracticable if said putlog could not be swung against said upright, unless the interstice in which the anchor plate has been inserted is in a certain position with relation to the upright. Also, 10 where the anchor plate is inserted close to an inside corner of a wall in order that the putlog may support the ends of the floor planks at the corner it becomes necessary to swing the floor supporting bar considerably out of 15 line with the anchor plate in order to reach a ledger board and upright. As the latter putlog necessarily is subject to more strain than the others shown in Fig. 1, it is desirable to make said putlog wider than the 20 others, which allows it to be swung a sufficient distance as in the construction of the putlog described the width of its inner end determines the range of angular movement 25 of the supporting bar with relation to the wall. The recess 20 prevents the anchor plate 16 from injuring the outer edge of its supporting brick. The putlog may be readily removed from the wall by lifting the anchor plate sufficiently to raise the lug 21 30 clear of the supporting brick 28 and then withdrawing the anchor plate.

While I have herein disclosed a single embodiment of my invention it is to be understood that it is but one of many which might be employed and still be within the scope of 35 the following claims.

I claim:

1. A putlog comprising in combination a 40 floor supporting bar, a recess at one end of said floor supporting bar, a rivet extending through said recess and secured to said floor supporting bar and an anchor plate pivoted

at one end on the portion of said rivet which is within said recess.

2. A putlog comprising in combination a 45 floor supporting bar, a projection formed at one end of said floor supporting bar, a U-shaped reinforcing stirrup secured to said projection in such a manner as to leave a space between the under side of said projection and the horizontal side of said U-shaped stirrup, a rivet extending through 50 said projection, through said space and through the horizontal side of said U-shaped stirrup with one end of an anchor 55 plate pivoted on the portion of said rivet within said space.

3. A putlog comprising in combination a 60 floor supporting bar, a projection formed at one end of said floor supporting bar, a U-shaped reinforcing stirrup secured to said projection in such a manner as to leave a space between the under side of said projection and the horizontal side of said stirrup, 65 a rivet extending through said projection, through said space and through the horizontal side of said stirrup and one end of an anchor plate pivoted on the portion of said rivet within said space, the portion of said anchor plate within said space being substantially of the same height as said space. 70

4. A putlog comprising in combination a 75 floor supporting bar, a recess in one end of said bar, one end of an anchor plate vertically pivoted in said recess, a rivet extending transversely through said recess and through a slot in said anchor plate.

In testimony whereof I have affixed my signature, in presence of two witnesses.

THOMAS H. KINGSTON.
